WILLIAM A. ELLISON, OF SALEM, MASSACHUSETTS, ASSIGNOR TO THE TURNER TANNING MACHINERY COMPANY, OF PORTLAND, MAINE, A CORPORATION OF MAINE

LEATHER STRETCHING AND TACKING MACHINE

Application filed April 13, 1927. Serial No. 183,501.

This invention relates to the stretching of hides, skins and pieces of leather and to their maintenance in stretched condition. The invention is illustrated as embodied in a machine for stretching skins and other relatively light pieces of leather and for tacking them in stretched condition upon suitable frames or stretcher boards. It is to be understood, however, that the invention and various important features thereof may have other applications and uses.

It is the common practice in a great many leather manufacturing plants, in performing stretching and tacking operations upon pieces of leather, first to tack each piece of leather by hand to a distensible frame and subsequently to distend the frame to put the piece of leather under tension where it is left until dry. These operations are laborious and require the exercise of very considerable skill for the reason that the various parts of a skin must be stretched by hand before tacking and the different parts must be stretched different amounts and in different directions according to the characteristics of the material which vary considerably in the different parts of each skin or other piece of leather. Furthermore, the stretching is carried out mostly with one hand while the other hand is used to position and drive the tacks in the material maintained in stretched condition by the first hand. While it may not be necessary to do so, it is a fact that most of the workers use their mouths as a magazine for the tacks, since it enables them to accomplish more work, perhaps because the tongue and lips may be employed in separating and successively positioning the tacks so as to be readily grasped by the hand. Because of these conditions it is becoming increasingly difficult to obtain workers to perform stretching and tacking operations and wages are correspondingly high. Moreover, in certain factories where it is desired to stretch skins and other like pieces of leather and maintain them in stretched position until they have dried, a well-known method consists in dipping each skin in a recepacle containing a gluey liquid, spreading it upon a stretcher board, and then smoothing and stretching it

out in all directions from a central portion of the skin by means of a manually operated slicker blade which removes the excess liquid and leaves the skin in a stretched, smoothed-out condition upon the board. If the work has been properly done the skin will remain adhering to the board in stretched condition until it dries. This method involves an even greater amount of laborious and disagreeable work than that inherent in the first-described method of stretching and tacking. Moreover, in both cases a great deal depends upon the worker, his skill and his endurance. Both the quantity and the quality of the work produced by each individual workman varies from day to day.

It is an object of this invention to provide skin stretching and tacking means for performing mechanically what has hitherto been accomplished only by hand, with the idea of securing increased production, raising the standard of quality and, particularly, securing a high degree of uniformity in the product.

To these ends and in accordance with an important feature of the invention, as herein illustrated, means is provided for stretching portions of a skin or other piece of leather from a central portion thereof outwardly toward its edges in the operation of which a predetermined tension developed in each given portion of the skin will determine the limit of the stretching operation for said given portion. Conveniently, a plurality of stretching devices are employed arranged for movement toward opposite edge portions of a piece of work and having gripper means for engaging edge portions of the piece of work, the arrangement being such that the stretching devices are thereafter moved simultaneously away from each other on opposite sides of the piece of work to stretch the piece simultaneously in all directions from a central portion thereof, securing means being provided controlled by the gripper means so as to secure the different stretched portions to a board or stretcher frame when a predetermined tension has been reached in the portion of the skin gripped by each individual gripper means. Preferably, and as illus-

trated, the gripper means associated with each stretching device has a part which serves as a feeler for contacting with the work to determine the extent of the movement of its associated stretching device in the direction 5 toward the center of the skin to engage the nearest edge portion thereof, the arrangement being such that the stretching devices come to rest after moving various distances 10 to engage the work, the distance being determined in each case through the co-operation of the feeler and the piece of work.

As illustrated, the means for securing the skin in stretched condition comprises a tacker mechanism associated with each stretching device and arranged to be controlled by the gripper means so that the tacker operates when a certain tension has been reached in the portion of the skin gripped by the gripper means. Conveniently the tacker has connections with its associated gripper to cause the latter to release the work at the instant the tack is driven. In the illustrated construction each tacker mechanism comprises 20 a spring operated driver adapted to be locked in raised position with the driving spring under tension, connections being provided between the gripper means and the locking means for the tack driver arranged to trip 25 the locking means when a predetermined tension is reached in the portion of the piece of work gripped by the gripper means.

Other features of the invention relate to improved means for depositing a tack in the 30 tacker mechanism wherein the tack depositing means is controlled by the movement of the combined stretching and tacking unit. Preferably too, and as shown, a movable chute or delivery tube is mounted for oscillation between a position where it supports a tack to a position for delivering the tack to a tack supporting throat in line with the driver of the tacking mechanism.

Still another feature of the invention relates to an improved table or work support 40 mechanism arranged to move the table or work support to work presenting position with respect to the stretching and tacking devices through operation of the means employed for starting the machine into operation.

These and other features of the invention will be described in detail in the specification and pointed out more particularly in the 45 appended claims.

In the drawings:

Fig. 1 is a view in side elevation illustrating one embodiment of the invention, that 50 part of the figure to the right of line A being designed to show supporting arms and tack chutes and other parts in side elevational view, while to the left of the line A parts have been broken away and other parts omitted to 55 show a single supporting arm and a stretch-

ing and tacking device together with part of the operating means therefor;

Fig. 2 is a detail view showing the work supporting table of the machine in lowered position;

Fig. 3 is a view of the table operating means taken along the line III—III of Fig. 2, looking in the direction of the arrows;

Fig. 4 is a sectional view through the raceway operating means showing the controlling clutch therefor in inoperative position;

Fig. 5 is a view similar to Fig. 4 with the clutch engaged;

Fig. 6 is a sectional view of the raceway driving means showing additional details including the primary driving shaft;

Fig. 7 is a detail view of the tack separating and tack delivering means;

Figs. 8 and 9 are detail views looking at the lower end of the raceway from above and illustrating the separation of a tack and its delivery to the upper end of a stationary chute;

Fig. 10 is a detail view taken along the line X—X of Fig. 7 looking in the direction of the arrows;

Fig. 11 is a detail view of a portion of a movable chute member;

Fig. 12 is a view in side elevation of one of the stretching and tacking devices on a larger scale than that of Fig. 1 and showing also a part of a similar device on the other side of the center of the machine together with the driving means for both devices, the driving means being in inoperative position;

Fig. 13 is a detail view of the driving means for the devices similar to the showing of said means in Fig. 12 but with the driving means in operative position, parts to the left of line B being in side elevation while to the right the parts are in section with the exception of shaft 260 of which the curved surface is shown;

Fig. 14 is a view similar to Fig. 13 showing the driving means for one device in inoperative position while the other is still operative;

Fig. 15 is a detail view in side elevation and partly in section disclosing part of the controlling means for the driving means of each stretching and tacking device or unit;

Fig. 16 is a view similar to Fig. 13 with the driving means of both devices operative for returning the devices along divergent paths to their initial positions of rest;

Fig. 17 is a detail view taken along the line XVII—XVII of Fig. 15, looking in the direction of the arrows;

Fig. 18 is a view of a stretching and tacking device or unit in side elevation and partly in section while the unit is moving toward the center of the machine;

Fig. 19 is a similar view while the unit is moving away from the center of the machine, the tack driver locked in raised position;

Fig. 20 is a view similar to Fig. 19 just after the driver has been tripped to drive a tack;

Fig. 21 is a plan view of the tack supporting jaws of the tacking mechanism looking from below;

Fig. 22 is a detail view of a gripper member of the work gripping means associated with each stretching and tacking device or unit; and

Fig. 23 is a detail view of part of the individual driving means for each stretching and tacking device or unit.

In the machine illustrated in the drawings for stretching and tacking hides, skins or leather pieces, a table 30 (Figs. 1 and 2) is provided for supporting a board 32 and a piece of work W while it is being stretched and tacked in stretched condition to the board. It is to be understood that a plurality of boards similar to that shown at 32 will be provided with each machine and that each board will be of a size to accommodate a skin or other piece of leather in stretched condition, and of a material suitable to receive and hold tacks utilized in securing the skin in stretched condition. For supporting the table 30 there is provided a plurality of posts or legs 34 secured to the under surface of the table and receivable slidably in standards 36 provided with sockets within which the posts 34 are vertically movable. For moving the table 30 from its lower work-receiving position (Fig. 2) to its work-presenting position illustrated in Fig. 1, there is provided a pair of levers, lever 40 being pivoted between brackets 42 securely attached to standards 36 and having at its free end a weight 44 (Fig. 1) for a purpose that will be presently described. The other lever 46 is carried by a pivot 48 (Fig. 3) supported in brackets 50, 51 extending toward each other from the other pair of standards 36.

At its free end the lever 46 carries a pin 52 (Fig. 1) adapted to be engaged by a spring pressed latch 54 to hold the table 30 in raised work-presenting position. When it is desired to release the table so that it may drop to work receiving position the operator operates the latch 54 by stepping on a treadle portion 56 thereof, a spring 58 being provided for returning the latch to operative position as soon as it is released by the operator. At their inner ends the levers 40 and 46 are pivotally connected to each other and to a link 60 by a pivot pin 62, the link 60 being pivotally secured at 64 to a bracket 66 extending downwardly from the central portion of the under surface of the table 30, the parts being so proportioned that the table is in elevated work presenting position when the lever 46 is held in latched position by the latch 54. Upon releasing the latch 54, the table at once drops by its own weight to work-receiving position, as indicated in Fig.

2, the weight 44 on lever 40 serving as a counterbalance to offset a great part of the weight of the table, thus permitting the table to descend without an undesirable amount of noise and vibration in operating the machine. For raising the table to work-presenting or operative position there is provided a lever 68 (Fig. 1) pivoted to bracket 51 (Fig. 3) and having a roll 70 for contacting with the free end of the lever 46 to depress the same upon downward movement of the lever 68 until the pin 52 is engaged under the latch 54, the operating lever 68 having a handle portion 72 adapted to be grasped by the operator for manipulating the operating lever 68 to cause upward movement of the table 30. It is to be understood that the pin 52 will be caused to ride down the slanting surface 74 on the latch 54, thereby causing rocking of the latch 54 to the right in Fig. 1 until the pin is properly engaged by the latch.

For stretching a skin or other piece of work supported on the board 32 there is provided a plurality of stretching mechanisms, each of which has associated therewith a tacker mechanism for securing a portion of the skin in stretched condition, the stretching mechanism and the tacker together constituting a stretching and tacking device or unit, indicated generally by the numeral 78, of which there are fifty in the illustrated machine, it being understood that the number may be varied to suit conditions imposed by different classes of work. Each unit 78 is guided and indirectly supported by a supporting arm 80 (Figs. 1 and 12) detachably secured to a circular frame member 82 in turn supported by bars, one of which is shown at 84 in Fig. 1 of the drawings, securely attached to an upright frame member 86, the said bars 84 serving also as supporting arms like the arms 80, each bar and each arm supporting one of the units 78.

Since each of the stretching and tacking units is like every other unit, a description of one will suffice for all. Referring particularly to Figs. 12 and 18 of the drawings it will be observed that each unit 78 comprises an L-shaped frame member 90, the upright part of the frame member being slotted at 92 (Fig. 18) to receive a sleeve member 94 which is interiorly screw-threaded for co-operation with a correspondingly exteriorly screw-threaded shaft 96. Preferably, and as shown, the sleeve 94 is mounted for vertical sliding movement within the slot 92 and for this purpose the sleeve 94 is provided with a pair of studs 98 on each side of the sleeve receivable in vertical slots 100 in the frame member 90. By reason of this pin and slot arrangement the frame 90 may adjust itself vertically to suit different thicknesses of work and to suit different positions of the board 32, since it is contemplated that the board 32 may carry a

skin or other piece of leather on each side thereof so that after one skin has been attached the board may be turned over to have a second skin attached and in its second position it will present a surface higher above the table 30 than in its preceding position. Upon reference to Figs. 12 and 18, it will be observed that the frame 90 has its upper end forked as at 91 to embrace slidably one of the arms 80 (or corresponding bar 84) thereby maintaining frame 90 upright as it is being moved by shaft 96, the entire weight of the unit 78 being carried (when the table 30 is in lowered position) by the shaft 96 which is supported by a bar 84 or an arm 80 in a manner presently to be described.

At the lower front end of the L-shaped frame member 90 there is provided a gripper member 102 adapted to co-operate with a pair of relatively thin-edged gripper rollers 104 (Fig. 21) carried at the lower end of a lever 106 pivoted at 108 to the frame 90. Each gripper member 102 has a number of relatively sharp ridges or corrugations 103 (Figs. 18 and 22) adapted to engage firmly the edge of a piece of work when the latter is gripped between the member 102 and the rollers 104. It will be observed upon inspection of Fig. 19 that when the gripper jaw 102 is in gripping position with respect to the rollers 104 the teeth or corrugations 103 are in front of or beyond a plane passing vertically through the centers of the rollers 104. Hence, any tendency of the rollers 104 to release the work by rotative movement is counteracted by an increased gripping of the curved surface of the rollers engaging with the adjacent corrugations, the result being that the work is securely gripped during the stretching operation and only released through operation of the gripper member or jaw 102, at the instant a tack is driven, as will be hereinafter described. In order that the gripper jaw 102 may not interfere with the driving of a tack into the work while the latter is held by the gripper, the said jaw is provided with a slot 103^a extending into the jaw sufficiently to permit a tack being driven while the jaw is in gripping position as shown in Fig. 19.

It will be observed that the gripper member 102 is pivoted at 105 to an arm 107 of a lever 109 pivoted at 110 to the lever 106. Connected to the pivot pins at 105, 110 is a link 111 serving with the arm 107 to form a fork 55 for embracing the gripper member 102 and providing the pivot support 105. Lever 109 is connected by means of a link 112 to a lever 113 pivoted at 115 to the frame 90 of its stretching and tacking unit 78. As will be hereinafter described the lever 113 operates the tack driver of a tacking mechanism which is associated with each stretching mechanism. Preferably, and as shown, the upper end of the link 112 is slotted as at 117 to receive a pin 119 secured to the lever 113 (Figs. 7 and

18). Pivotedly secured to a boss 116 projecting from the gripper member 102 is a rod 118, the other end of which passes slidably through an opening in a bracket member 120 secured to frame 90, a light spring 122 being interposed between the bracket 120 and a shoulder 124 at the pivoted end of the rod 118. As shown, the spring 122 is coiled upon the rod 118 and serves to hold the gripper member 102 in operative relation with respect to the gripper rollers 104. When an edge portion of the work is encountered during movement of the unit 78 toward an edge portion of the work, the gripper rollers ride up over the edge before the gripper member 102 engages the work since the rollers during this movement of the stretching and tacking unit 78 are in advance of the gripper member 102. Hence, by the time that the gripper member 102 reaches the work, the edge of the latter is held down firmly by the rollers 104 on the supporting board 32. Upon contacting with the firmly pressed work, the member 102 yields against its spring 122, thus performing an important function as will presently be described. This retraction of the member 102 through its engagement with the stationary edge of the work causes tipping of the member 102 about its pivot 105 with the result that the extreme forward edge of the member 102 is pressed downwardly against the supporting board 32 in such a position as to insure its engagement under the edge of the work. This engagement readily takes place during the further movement of the unit 78 in the direction to engage the work, since during this time the rollers leave the extreme edge portion of the work and press firmly on the work always in advance of the forward edge of the member 102 so that the work is free to be lifted by the forward edge of the latter which is engaged as described quite firmly with the supporting board 32. Upon movement of the stretching and tacking unit 78 in the opposite direction the edge portion of the piece of work is even more firmly gripped than before, member 102 being aided in its gripping movement by the spring 122 and by the pressure of the rollers 104 which press the edge portions of the work against the sharp ridges or teeth 103 on the gripper member 102. While Fig. 18 illustrates the movement of the stretching and tacking unit 78 by which the gripping means is caused to engage the work, Figs. 19 and 20 illustrate movement of the unit 78 in the reverse direction, as indicated by the arrows in these figures, to stretch the engaged portions of the work. When the end of the gripper member 102 contacts with an edge portion of the work which at the time is held down firmly by the over-riding rollers 104 the member 102 is retarded sufficiently to swing its projecting end 126 in an upward direction thereby swinging a lever 128 about its pivot 130 by reason of a

pin and slot connection 132, 134 between the part 126 and the lever 128. The swinging of the lever 128 in the direction indicated pulls downwardly upon a rod 136, thereby yielding 5 pulling upon a pawl 138 pivoted at 140 to the frame member 90. In this way the pawl 138 is caused to engage one of a plurality of teeth 142 on a bar 144 which is slidably mounted in a guideway 146 on the moving 10 frame 90 and a second guideway 148 (Fig. 12) carried by a stationary bracket 150 securely attached to a larger bracket or post 152 projecting downwardly from the bar 84 or from one of the arms 80. When the gripper 15 member 102 engages with an edge of the work and has its end retarded thereby as just described, it causes the pawl 138 to engage with the tooth 142 on the bar 144 and hence the bar 144 is moved along with the unit 78 until 20 a latch 154 (Figs. 12 and 15) strikes against the lower end of a trip lever 156. When this occurs the trip lever is caused to swing about its pivot 158 (Figs. 15 and 17) thereby withdrawing its latching end 160 away from a 25 shoulder 162 on an adjustable latch member 164 adjustably secured to a carrier 166. When the carrier 166 is thus released it slides upwardly on supporting post 152 being connected thereto by studs 167 on the carrier 30 movable in slots 169, in the post 152, a spring or springs 168 being provided to effect in a prompt manner such upward movement of the carrier, and in this way the shaft 96 has its pinioned end 170 (Fig. 12) lifted away 35 from a large bevel gear wheel 172, thereby terminating rotative movements of the shaft 96 and bringing the unit 78 to a stop. In this way the gripper member 102 serves also as a 40 feeler for contacting with the work and determining the extent of inward movement of each of the units 78. From this viewpoint the gripper member 102 may be regarded as a feeler for the work which is controlled by the work to initiate disconnection of the unit 78 45 from its moving means. Since the piece of work, especially if it be an untrimmed skin, is very irregular in contour, it follows that the different stretching and tacking units 78 will travel different distances, although all 50 start at the same distance from the center of the machine, so that it is the work which, as a matter of fact, controls the amount of travel of each unit 78 in its movement to engage the nearest edge portion of the work. After all of the units 78 have come to rest 55 through tripping of each individual operating shaft 96, all of these shafts 96 are simultaneously reconnected to the large bevel gear 172 which, at this time, is rotating in the reverse direction so that all of the units 78 are caused to move away from the center of the machine along divergent paths to stretch the skin or other piece of work simultaneously 60 in all directions. This reverse driving means 65

for the shafts 96 will be described later in the specification.

Besides the gripper means 102, 104 carried by the frame 90 there is provided a tacker mechanism carried by the same frame and forming part of the stretching and tacking unit 78. Referring again to Fig. 18 it will be observed that the tacking mechanism comprises a barrel or casing 180 for a driver bar 182 carrying a tack driver 184, the driver bar in this figure being shown locked in raised position by means of a lock 186 slidable in a guideway 188 in the side of the casing 180 to engage with one of the teeth 190 on the adjacent side of the driver bar 182. The outer end of the lock 186 passes through a forked projection 192 on the lever 106, the lock 186 being pressed against the driver bar 182 by means of a spring 194, the lock 186 being provided with a ball stop 196 engaged in a socket provided in the forked projection 192. The lever 106 is held normally in such a position by a spring 198 that the spring 194 may be operative to hold the lock 186 with its operative end engaging one of the teeth 190 on the driver bar 182, a shoulder for limiting the movement of the lever 106 by the spring 198 being provided by a projection 200 on the frame 90. When the pull on the gripper member 102 and grip rollers 104, 70 exerted by the gripped portion of the work during movement of the unit 78 away from the center of the machine, becomes great enough to overcome the tension of the spring 198 the latter yields in which case the gripper member 102 and the grip rollers 104 are retarded in their movement so that they lag 75 behind the movement of the unit 78, thereby swinging the lever 106 on its pivot 108 and causing movement of the lock 186 to withdraw its operative end from engagement with the selected tooth on the driver bar 182. The latter is instantly forced down by its driving spring to drive a tack. Hence, just an instant before the gripping means, comprising 80 the gripper member 102 and the grip rollers 104, lets go of the work a tack is driven into the edge portion thereof to hold it in stretched condition. It will be readily understood that the tension of the spring 198 is an important 85 factor in determining the amount of stretch to be given to the portion of the work gripped by the unit of which this spring is a part. As already explained, the gripping means, 90 comprising the gripper member 102 and the gripper rolls 104, hangs on to the work until the spring 198 yields sufficiently to trip the driver bar 182. When this occurs the driver lever 113 instantly forces the driver bar 182 95 downwardly in a tack driving operation and at the same time the gripper member 102 is retracted to release the work. It follows that if the tension of the spring 198 be increased 100 by adjustment of the adjusting screw 199 (Fig. 18) the greater the tension on the 105 110 115 120 125 130

gripped portion of the work will be before it is released. Hence, the amount of stretching of each given portion of the skin and for various classes of skins may be regulated by properly adjusting the tension of the various springs 198 in the stretching and tacking units 78. This tension on the spring 198 of a unit which is to engage the butt end of a skin will probably be somewhat greater than the tension of the spring 198 in a unit which is to engage the more yielding flank portions of the skin. This, however, is a matter which comes within the province of the operator who should be skilled in judging the stretching qualities of the skins in the batch to be operated upon in any given working day. In order to insure that the work will be freed from the grip of the gripping member 102 and the gripper rollers 104, connections are provided between the driver lever 113 and the gripper member 102 by means of the link 112 connecting the driver lever 113 and the lever 109 to which the gripper member 102 is pivoted as has already been described. When the driver bar is approaching its lowest position the pin 119 carried by the lever 113 contacts with the wall at the lower end of the slot 117, thereby forcing the link 112 downwardly and rocking the lever 109 on its pivot point 110 to withdraw the gripper member 102 in an upward and rearward direction, thus freeing the work. Upon reference to Figs. 12 and 18 it will be seen that a spring 204 connected at its upper end to a pin 206 secured to the frame member 90 and at its lower end to a pin 208 fixedly secured to the lever 113 pivoted at 115 on the frame member 90 serves as the driving spring for the driver bar 182 and driver 184, since one end of the lever 113 is connected to the upper end of the driver bar 182 by means of a pin 214 on the driver bar engaged in a slot 216 (Fig. 12) in the end of the lever 113. When the stretching and tacking unit 78 is approaching the limit of its stretching movement away from the center of the machine, a roll 218 (Fig. 12) on the free end of the lever 113 engages with a downwardly projecting end 220 (Fig. 1) of one of the arms 80 (or with the standard 86 in case of a unit guided on bar 84) so that during the latter part of the described movement of the unit the lever 113 has its roll carrying end depressed, thus putting the spring 204 under tension and elevating the driver bar 182 to its highest position in which position it is locked by the lock 186.

The tacker mechanism which forms part of the unit 78 also comprises a tack supporting means for holding the tack in position beneath the driver, the said means comprising a throat or pocket 222 open at its upper end through which the tack is dropped by means which will hereinafter be described. The bottom of the pocket 222 is made up of two members 224, 226 (Figs. 18 and 21). Of

these member 224 is pivoted by a vertical pin 228 to a portion of the frame 90 while the other member 226 is integral with the adjacent portion of the frame 90. As shown, the pivoted member 224 is held yieldingly against a vertical edge of the member 226 by means of a curved leaf spring 230, the forward end of member 226 having a slot at 232 to permit escape of the shank of the driven tack. At the bottom of the cup 233 formed in the members 224, 226 is a small opening 234 located in member 224 for receiving the small end of the tack, the opening 234 being, however, insufficient in size to permit the tack to drop down with its shank in the opening. When the driver 184 is projected downwardly, the force of the blow drives the tack through the opening 234, spreading apart the members 224, 226. As the unit 78 continues to travel after the driving of a tack, the members 224, 226 separate sufficiently to escape from the driven tack, the head of the tack passing through an opening 236 in the side of the pocket 222, as most clearly shown in Fig. 18.

As has already been stated each stretching and tacking unit 78 is moved in reverse directions by one of a plurality of shafts 96. As shown most clearly in Figs. 1 and 12, each shaft 96 is pivotally supported at one end by means of a bearing 239 pivoted at 240 to a bracket 242 fixedly attached to the standard 86 or (where the arms 80 are secured only to the hub 82) to an upright portion 220 (Fig. 1) of one of the arms 80. At its other end the shaft 96 is supported in a bearing 244 (Fig. 15) furnished by the carrier 166. When the carrier 166 is in raised position the pinioned end 170 (Fig. 12) of the shaft 96 is lifted away from the large bevel gear 172. In other words, the shaft 96 is then in idle or inoperative position. On the other hand, when the carrier 166 is forced downwardly until it is engaged by the latch 156, the shaft 96 is brought into engagement at its pinioned end 170 with large bevel gear 172 and thus becomes operative by its rotation to cause movement of the stretching and tacking unit 78. The means by which, in the illustrated construction, the shafts 96 are caused to rotate first in one direction and then in the reverse direction will now be described. Referring again to Fig. 1 of the drawings, it will be seen that a main shaft 250 is provided adapted to receive power from any suitable source applied to a pulley 252 at one end of the shaft. At its other end the shaft 250 is provided with a bevel pinion 254 which is adapted to mesh with either one of two relatively large bevel gears 256, 258, both of which are keyed to slide axially on and rotate with a vertical shaft 260 (Fig. 12) mounted for rotation in bearings 262, 264 provided in the frame of the machine. Secured fixedly to the lower end of the shaft 260 by a key 261 (Fig. 13) is the large bevel gear 172 al-

ready mentioned as the driving means for the shafts 96. Surrounding the shaft 260 within the bearing 264 is a sleeve 266 having a portion projecting below the bearing 264 to which is secured a disk 270 (Figs. 12 and 13), the disk being mounted so that it does not turn with the shaft 260 although it moves with the sleeve 266 during vertical reciprocations thereof. Interposed between the disk 270 and the bevel gear 172 and surrounding the shaft 260 is a spring 272 which tends constantly to move the disk 270 and sleeve 264 in an upward direction whereby the bevel gear 256 may be caused to mesh with the pinion 254. In Fig. 12 of the drawings the stretching and tacking units 78 have all reached their positions of rest at the outer ends of their divergent paths and at this time the shafts 96 are in inoperative position each with its pinioned end 170 raised above the large bevel gear 172. To start the machine in operation the operator depresses the handle 72 (Fig. 1) of the lever 68 which is connected by a link 274 with the outer end of a lever 276 pivoted on the frame of the machine at 278 and having a yoke portion 280 which embraces and is secured to a collar 282 freely rotatable in a groove formed in the attached hubs of the gear wheels 256, 258. Upon depressing the handle 72 the gears 256, 258 and the sleeve 266 are caused to move downwardly bringing the bevel gear 258 into mesh with the bevel pinion 254 and at the same time the disk 270 is caused to operate a plurality of bell-crank levers 290 each pivoted at 292 (Fig. 15) to a bracket 294 rigidly attached to the bracket or post 152. Each bell-crank lever 290 has an arm 296 which carries a roll 298 for engagement with the disk 270 and also another arm 300 adapted to engage with a pin 302 slidably supported in the carrier 166 by a spring 304. When the bell-crank lever 290 is rotated in a counter-clockwise direction by depression of the disk 270 from the position shown in Fig. 12 to that shown in Fig. 13, the arm 300 of the bell-crank is caused to press downwardly upon the pin 302 which through the spring 304 operates to depress the carrier 166 to such a point that the shoulder 162 on the carrier 166 is engaged by the latch 156 whereby the carrier is held in depressed position with the pinioned end 170 of each shaft 96 in meshing engagement with the large bevel gear 172 (Fig. 13). In this way all of the shafts 96 are rocked simultaneously into operative engagement with the bevel gear 172 and are caused to rotate, thus moving all of the stretching and tacking units 78 simultaneously toward the center of the machine. As soon, however, as the gripper member 102 engages firmly with an edge portion of the piece of work, during movement of a unit 78 toward the center of the machine, the bar 144 is operated, as hereinbefore described, to cause movement of the latch 156 to inoperative or unlatching position with respect to its associated carrier 166 thereby permitting the carrier to rise under the action of the spring 168, whereby the shaft 96 is lifted out of operative position and the stretching and tacking unit 78 comes to a stop with an edge portion of the work engaged by the gripping means. As the carrier 166 rises the bell crank lever 290 is caused to move to the position shown in Fig. 15, that is, with the roll 298 pressing against a vertical edge portion of the disk 270 instead of engaging with the upper surface of the marginal portion of the disk, as in Fig. 13, when the disk 270 was first depressed. In Fig. 14 the bell crank at the right of the figure has moved to the position indicated in Fig. 15 while the other bell crank in Fig. 14 is still engaged with the top marginal surface of the disk 270. This means that the stretching and tacking unit corresponding to shaft 96 at the left in Fig. 14 is still moving toward the edge of the work or toward the center of the machine while that at the right has ceased moving, having gripped an edge portion of the work. In order to insure that the roll 298 on the arm 296 of the bell crank lever 290 will be moved away from the top marginal surface of the disk 270 upon the described upward movement of the carrier 166 there is provided on the carrier a slanting or cam surface 306 (Fig. 15) adapted to engage with a roller 308 supported by arm 310 of the bell crank lever 290 whereby the bell crank lever 290 is forced to the position shown in Fig. 15 depressing the pin 302 against the spring 304, the effect, however, not being sufficient to depress the carrier 166 far enough against the tension of the spring 168 to cause reengagement of the latch 156. In other words, the carrier 166 is not depressed to its latched position where the shaft 96 will again become operative. The disk 270 remains depressed in the position shown in Figs. 13 and 14 until the last bell crank is released in the manner shown in Fig. 15. When the last bell crank 290 is released the disk 270 is at once moved upwardly by the spring 272 and in doing so it forces all of the bell cranks 290 to turn in a counter-clockwise direction, thereby depressing every one of the carriers 166, through pressure of the arm 300 of each bell crank upon the pin 302 in the carrier 166, to such an extent that each latch 156 again locks its associated carrier 166 in its depressed position whereupon all of the shafts 96 again become operative, as indicated in Fig. 16. This time, however, the shaft 260 is turning in a direction the reverse of that in which it was turning when all of the shafts were first engaged upon the depression of the handle 72 by the operator. The reason for this lies in the fact that upon upward movement of the disk 270 and sleeve 264 the lower bevel gear 256 is moved upwardly and brought into mesh

with the bevel pinion 254 and hence the direction of rotation of the vertical shaft 260 is changed. Hence, with the disk 270 in the position shown in Fig. 16, with the carriers 166 depressed, the shafts 96 are driving the stretching and tacking units away from the center of the machine and, therefore, these units are operating simultaneously to stretch all gripped portions of the piece of work and 5 to tack them at various times as the tension in the stretched portion of the skin causes each gripping means in turn to let go, with the result that a tack is driven to hold the stretched portion in stretched condition, it 10 being understood that the tacking takes place while the gripping means is releasing the edge of the gripped portion of the piece of work so that the tacking takes place before the work is actually released by the gripping 15 means. As each stretching and tacking unit 20 arrives at the position shown at the left in Fig. 12 it moves the bar 144 to the left by engagement of the upright edge of the frame 90 with a stop block 320 (Fig. 1) at the outer 25 end of the bar 144. As the bar 144 is thus dragged to the left in Figs. 1 and 12, the latch 154 is dragged back from its position shown in Fig. 16 to the position shown in Fig. 12 and during this movement it causes disengagement of the latch member 156 from the 30 carrier 166, thereby permitting the associated carriers 166 to rise whereby the shaft 96 is rendered inoperative through the raising of its pinioned end 170 away from the bevel gear 172. At the very end of the outward movement of the units 78 the tack drivers are all 35 reset in raised position through depression of the roller carrying end of each driver lever 113, as before described.

40 Just as each stretching and tacking unit 78 reaches its outermost position of rest, as described, or shortly thereafter, it receives a tack which is dropped into the tack pocket 222 by means of an oscillatory chute section 330. The mechanism for delivering a tack from the magazine hopper 332 (Fig. 1) to the delivery chute section 330 will now be 45 described. As shown, the hopper 332 has a hinged cover 334 which may be swung open 50 to permit a quantity of tacks to be dumped into the hopper 332. In accordance with a well-known arrangement, the tacks slide in a mass from the hopper into a rotating magazine 336 which is constantly rotating, being 55 driven by a chain 338 which passes around a sprocket wheel (not shown) for the magazine 336 and also around a sprocket wheel at the right-hand end of a shaft 340 which carries at its left-hand end (Fig. 1) a second 60 sprocket wheel adapted to be engaged by a chain 342 which also engages with a sprocket (not shown) on the power shaft 250 of the machine. Hence, the magazine 336 is being 65 constantly driven to feed tacks to a stationary raceway section 344. Since mechanism

for delivering tacks from a magazine to a raceway section is old and well known, as shown for instance in Patent No. 429,527, granted June 3, 1890, upon application of J. Hyslop, it is not shown nor described in detail. For receiving the tacks from the raceway section 344 there is provided a raceway section 346 mounted upon an arm 348 carried by a collar 350 fixedly secured to the upper end of a short, vertical shaft 352 which 70 is mounted in a bearing 354 provided by bracket 356 carried by the frame of the machine. Below the bearing 354, the shaft 352 carries a bevel gear 358 (Fig. 6) which is constantly in mesh with a bevel pinion 360 75 carried loosely by a stub shaft 362 supported in bearings provided by the bracket 356. At its other end the shaft 362 carries a bevel pinion 364 which is constantly in mesh with a bevel pinion 366 at the upper end of a 80 vertical shaft 368 which carries at its lower end a bevel gear 370 in mesh with a bevel gear 372 secured to power shaft 250 which is constantly rotating as long as power is supplied to the machine through the pulley 352. 85 As shown in Fig. 6 the shaft 362 is provided with a clutch member 374 which is rotatable with the shaft 362 and also slidable thereon into and out of engagement with a corresponding clutch member 376 which is securely attached to the bevel pinion 360. The arrangement is such that when the clutch members 374, 376 are disengaged, as shown 90 in Fig. 4, the raceway section 346 becomes stationary and this occurs when the raceway 100 section 346 is in line with the raceway section 344, as illustrated in dotted lines in Fig. 1. To insure that this action takes place there is provided on the bevel gear 358 a roller 105 stud 378 which engages with rounded end 380 of a clutch lever 382 to throw the latter over to the left, as indicated in Fig. 4, the movement of the lever being effected, in part, by the relatively light spring 384. In order 110 to cause re-engagement of the clutch members 374, 376 there is provided an actuating means controlled by upward movement of the vertically movable beveled gears 256, 258. As will be clear from an inspection 115 of Fig. 5, upward movement of the bevel gear 258 will cause upward movement of an operating block 390 which is mounted for vertical movement in a flange 392 projecting from the bracket 262 (Figs. 1 and 6). At 120 its lower end the block 390 carries a roll 394 which rides on an annular projection 396 (Figs. 4 and 5) on the upper surface of the bevel gear 258. The block 390 also carries a pawl 398 pivoted thereto and operative to contact with a roll 400 at the lower end of the clutch lever 382 to cause movement of said clutch lever in a clockwise direction about its pivot point 402, thereby throwing 125 in the clutch comprising members 374, 376, the clutch remaining engaged because of the 130

frictional engagement of the teeth in spite of the pull of the light spring 384. As soon as this takes place the vertical shaft 352 is caused to rotate whereby the raceway section 346 is operated to swing its lower end in a circle past the upper ends of stationary chute sections 404 (Fig. 1). While the lower end of the raceway section 346 passes each chute section 404 it drops a tack therein, as will be hereinafter described. While the block 390 with its pawl 398 caused the throwing in of the clutch 374, 376 on upward movement of the block, downward movement of the block 390 will have no effect on the clutch member since the pawl 398 will swing idly on its pivot during the downward movement of said block which takes place when the machine is started in operation by depression of the handle lever 68 (Fig. 1).

As before stated the lower end of the raceway section 346 delivers a tack to the upper end of each chute section 404 in turn as it swings around a complete circle, separation of the tack from others at the lower end of the raceway and delivery to the chute section 404 being accomplished by means shown most clearly in Figs. 7, 8 and 9. From an inspection of these figures it will be observed that the raceway section 346 is provided at its lower end with a tack separator comprising a slide 406 which carries at its upper end two picker plates 408, 410 spaced from each other in the direction of the length of the raceway section 346 and having their beveled ends spaced from each other sufficiently to permit the shank portion of a tack to pass between them upon movement of the two picker plates from the position shown in Fig. 9 to that shown in Fig. 8. Upon reverse movement, the next tack slides down so that its shank portion is resting upon the beveled edge of the lower picker plate 410, as indicated in Fig. 9. For causing the described movements of the slide 406 and its attached picker plates 408, 410 there is provided a link lever 412 pivoted at 414 to the block 406, a spring 416 being provided for moving the lever 412 back to its normal position of rest after it has been moved through contact with one of the chute sections 404. For this purpose the spring 416 has one end attached to a stud 418 and its other end to the pivot 414 of the lever 412 and intermediate its ends is engaged with a stud 420 carried by the rear end of the lever 412. Upon movement of the lower end of the raceway section in the direction of the arrow in Fig. 8 the rounded end of the lever 412 contacts with the rounded periphery of the chute section 404 and is displaced relatively to the raceway in a direction to move the slide 406 and its picker plates 408, 410 to the left, that is from the position shown in Fig. 9 to that shown in Fig. 8, thereby causing the separation of a tack which is dropped into the open end of the chute section 404 when the end of the raceway comes opposite a slot 422 in the side of the chute section 404. After the raceway has passed on dragging the yielding lever 412 by the chute section 404 the slide 406 is returned together with its picker plates 408, 410, to initial position shown in Fig. 9. When the tack drops into the upper open end of the chute section 404 it comes to rest upon a plate 430 (Figs. 7 and 10) which normally rests with a portion thereof intersecting the plane of the chute section 404, as shown in dotted lines in Fig. 10. The plate 430 is pivoted at 432 to a supporting bracket 434 supported by one of the arms 80 or by one of the frame members 84, the plate 430 being held in its tack supporting position, with the tack chute 330 out of alignment with the chute section 404 as indicated in dotted line positions of the parts in Fig. 10, by means of a spring 438 secured at one end to a pin 440 on the bracket 434 and at its other end to a pin 442 upon a link 444 pivoted at 446 to the plate 430 and having at its other end a cross bar 448 having at one end a block 450 pivoted thereto at 452, the said block being slidable in the guide-way 454 while the other end of the cross bar 448 carries a roller 456 which is adapted to be engaged by a vertical edge portion of the frame 90 of one of the stretching and tacking units 78. Just as the stretching and tacking unit 78 is reaching its outermost position of rest the frame 90 thereof contacts with the roll 456, as indicated in Fig. 7, and causes swinging of the plate 430 and with it the chute section 330 which is thus rotated through 45° to bring its lower, offset end 458 directly over the tack pocket 222, and its open end in alignment with the chute section 404, whereupon the tack drops into the pocket. It will be clear that as soon as each stretching and tacking unit 78 starts on its journey toward the center of the machine the chute section 330 and its attached plate 430, will be rotated by spring 438 back to dotted line position (Fig. 10) in which the plate 430 serves as a tack support preventing escape of the tack from the upper stationary chute section 404 in which it is dropped from the raceway section 346 in the manner already described.

In the operation of the machine a piece of work, such as a skin, is placed upon a board 32 and the board and skin introduced into the machine by sliding the board over the table 30 while the latter is in depressed position, as indicated in Fig. 2, the operator taking care to position the board 32 with the skin thereon located with its central portion beneath the vertical shaft 260 at the center of the machine. The machine is then started in operation by depressing the starting lever 68 which, through the roll 80 operates the table lifting lever 46 to cause elevation of the table to work presenting position wherein

it is locked by the latch 54 in the manner already described. At the same time that the table is elevated the gears 256, 258 and the sleeve 266 are moved downwardly by reason of the connecting link 274 from the starting lever 68 to the gear moving lever 276. When the gears 256, 258 and sleeve 266 are moved downwardly, the disk 270 is also moved downwardly, and in doing so it operates simultaneously all of the bell crank levers 290 by which the carriers 166 are depressed to move the shafts 96 carried thereby into engagement with the large pinion gear 172, thus starting the machine in operation, since each shaft 96 causes movement of its associated stretching and tacking unit 78 toward the center of the machine, thus enabling the gripping means carried by each unit to engage the nearest edge portion of the work. When a gripper member 102 engages an edge portion of the work, it causes disconnection of the associated driving shaft 96 so that the stretching and tacking unit comes to a stop, each unit when it has engaged its portion of the work. When the last unit has come to rest the disk 270 is released from the bell crank levers 290 and in rising causes such a movement of the bell crank levers as to depress all of the carriers 166 to their lowermost latched positions wherein all of the shafts 96 are reconnected to the large bevel gear 172 which, at this time, is traveling in a reverse direction to that which it had at the starting of the machine. Hence, all of the stretching and tacking units 78 are caused to move simultaneously away from the center of the machine, thus placing the work under tension in all directions, stretching each portion according to the amount of natural stretch therein. Finally, when the tension on a given portion becomes greater than the tension of the spring 198 of the gripping means the latter commences to lag behind its unit and this results in the driving of a tack which takes place before the work is actually released by the gripping means. Hence, all parts of the work are held either by the gripping means or by a tack until every part is tacked with the skin secured in stretched condition. Return of the stretching and tacking units 78 to their initial positions of rest results in disconnecting the shafts 96 from the driving gear 172 and the parts are at rest with the table still locked in raised position. The operator may now step upon the tread portion 56 of the latch 54, thereby permitting the table to descend to a position where the piece of work may be readily removed and replaced by another piece of work.

Having thus described my invention, what I claim as new and desire to secure by Letters Patent of the United States is:

1. In a machine for stretching hides, skins, leather and other similar pieces of work and securing them in stretched condition, a sup-

port having a surface upon which a piece of work may be spread out, means comprising members movable over the surface of the support toward all sides of the piece of work on the support constructed and arranged to grip edge portions of the piece of work, said members being subsequently operative for stretching the piece of work simultaneously in all directions from a central portion thereof, and means for securing the piece of work along edge portions thereof while under tension. 75

2. In a machine for stretching hides, skins, leather and other similar pieces of work and securing them in stretched condition, a support having a surface upon which a piece of work may be spread out, means comprising members movable over the surface of the support toward opposite sides of the piece of work on the support constructed and arranged to grip edge portions of a piece of work, said members being subsequently movable in reverse directions to effect stretching of portions of the work away from each other upon opposite sides of a central portion thereof, and means for securing said edge portions while under tension. 80

3. In a machine for stretching hides, skins, leather and other similar pieces of work, a support having a surface upon which a piece of work may be spread out, and means comprising members movable over the work supporting surface of the support for engaging edge portions of a piece of work and for stretching the piece of work, said members being constructed and arranged to release each edge portion of the work when a predetermined tension is reached therein. 95

4. In a machine for stretching hides, skins, leather and other similar pieces of work and securing them in stretched condition, a work support having a surface upon which a piece of work may be spread out, a plurality of devices movable over the work supporting surface of the support to engage and grip edge portions of a piece of work on the support, and means for causing the described movement of the devices and also movement of the devices in reverse directions so that the work may be stretched during movement of the devices away from each other, each device having means for securing in stretched condition a portion of the work engaged by the device. 105

5. In a machine for stretching hides, skins, leather and other similar pieces of work, a support having a surface upon which a piece of work may be spread out flat, and means comprising grippers for engaging edge portions of a piece of work and movable away from each other for stretching the piece of work simultaneously in all directions from a central portion thereof, said grippers being constructed and arranged to release each edge portion of the work when a predetermined tension is reached therein. 115

6. In a machine for stretching hides, skins, leather and other similar pieces of work and securing them in stretched condition, a support for a piece of work, stretching means guided for movement to engage edge portions of a piece of work and for movement in a reverse direction to stretch the work, and securing means associated with the stretching means and arranged to be controlled by the tension developed in the portions of the work engaged by the stretching means, whereby successive portions of the work are secured in stretched condition as a predetermined tension is reached in each portion thereof. 10
7. In a machine for stretching hides, skins, leather and other similar pieces of work and securing them in stretched condition, a support having a surface upon which a piece of work may be spread out flat, means having grippers movable over the work supporting surface for engaging and picking up edge portions of a piece of work on the support, said grippers being movable in reverse directions for stretching the work, means associated with each gripper for securing the work in stretched condition, and connections between each gripper and its associated securing means to determine the time of operation of the latter means. 20
8. In a machine for stretching hides, skins, leather and other similar pieces of work and securing them in stretched condition, a support for a piece of work, means having grippers for engaging edge portions of a piece of work on the support, means to move the grippers to effect a stretching of the piece of work, a securing means associated with each gripper to effect securing of the work when a predetermined tension has been established between the gripper and the gripped portion of the work, and means operated by the securing means to cause its associated gripper to release the work following the securing operation on the gripped edge of the work. 30
9. In a machine for stretching hides, skins, leather and other similar pieces of work and securing them in stretched condition, a support for a piece of work, means comprising grippers for engaging edge portions of a piece of work, means to move the grippers to effect a stretching operation on the work, securing means associated with each gripper and arranged to be controlled by the gripper to effect securing of the portion of work held by the gripper when a predetermined tension of the work has been reached, and connections between the securing means and its associated gripper to effect release of the work from the gripper immediately after the operation of the securing means. 40
10. In a machine for stretching hides, skins, leather and other similar pieces of work, a support for a piece of work, a plurality of devices each having a gripper for engaging an edge portion of a piece of work, means individual to each device for effecting movement thereof in a direction toward the work and controlled by the gripper to terminate the movement of the device when the work has been securely gripped, and means for simultaneously reversing the movement of all of the devices to effect a stretching operation on the piece of work. 50
11. In a machine for stretching hides, skins, leather and other similar pieces of work, a support for a piece of work, a plurality of devices each comprising means for engaging an edge portion of a piece of work, means for effecting movement of said devices toward the work and causing said devices to pick up and engage the work, and means automatically operative for reversing the movement of the devices to effect a stretching operation on the piece of work. 60
12. In a machine for stretching hides, skins, leather, and other similar pieces of work, a support for a piece of work, a plurality of stretching devices movable for engaging edge portions of a piece of work on the support, means for moving the devices toward the work, a feeler mechanism associated with each device for engaging the work and operative to control the moving means for the devices so as to terminate the movement of each device after the latter has engaged with an edge portion of the work, and means for causing simultaneous movement of the devices away from each other on opposite sides of the work to effect stretching of the piece of work. 70
13. In a machine for stretching hides, skins, leather and other similar pieces of work and securing them in stretched condition, a work support, and a plurality of devices movable to engage a piece of work, each device having a gripper for picking up and gripping an edge portion of the piece of work so that the work may be stretched during movement of the devices away from each other, each device also having means controlled by its associated gripper for securing in stretched condition a portion of the work operated upon by the associated gripper. 80
14. In a machine for stretching hides, skins, leather and other similar pieces of work, a support for a piece of work, a plurality of devices having each a gripper for engaging edge portions of a piece of work on the support, means for moving the devices toward the work, each gripper having a feeler associated therewith for engaging with the work and operative to control the moving means for the devices so as to terminate the movement of each device after the gripper has gripped an edge portion of the work, and means for causing simultaneous movement of the devices away from each other on opposite sides of the work to effect stretching of the piece of work. 90
15. In a machine for stretching hides, 100

- skins, leather and other similar pieces of work and securing them in stretched condition, a support for a piece of work, a plurality of stretching and tacking units movable toward edge portions of a piece of work on the support to engage said edge portions and subsequently movable away from each other upon opposite sides of a piece of work to stretch the work in many directions from a central portion thereof, means for causing the described movements of the stretching and tacking units, and means controlled by the work for determining the extent of movement of each unit when moving to engage the work. 5
16. In a machine for stretching hides, skins, leather and other similar pieces of work and securing them in stretched condition, a support for a piece of work, a plurality of stretching and tacking units movable toward edge portions of a piece of work on the support to engage said edge portions and subsequently movable away from each other upon opposite sides of the piece of work to stretch the piece of work away from a central portion thereof, means for moving the units to cause them to engage edge portions of the work controlled by the work so that each unit stops when an edge portion has been seized by the unit, and means for automatically moving the units away from each other upon opposite sides of the piece of work to effect stretching thereof. 10
17. In a machine for stretching hides, skins, leather and other similar pieces of work and securing them in stretched condition, a support for a piece of work, a plurality of stretching and tacking units movable to engage edge portions of a piece of work on the support and subsequently movable away from each other upon opposite sides of the piece of work to effect stretching thereof, means individual to each unit for moving it in the direction described, means controlled by the work for rendering the moving means of each unit inoperative when its associated unit has engaged with an edge portion of the work, and means for again rendering all of the moving means for all of the units operative whereby the units are caused to stretch portions of the work in opposite directions from a central portion thereof. 15
18. In a machine for stretching hides, skins, leather and other similar pieces of work and securing them in stretched condition, a support for a piece of work, a plurality of stretching and tacking units movable to engage edge portions of a piece of work on the support and subsequently movable away from each other upon opposite sides of the piece of work to effect stretching thereof, a shaft individual to each stretching and tacking unit for causing the described movements thereof, a gear for driving all of the shafts, means controlled by the work for causing disconnection of each shaft from the driving means when its associated unit has engaged with the work, and means for causing re-engagement of all of the shafts with the driving means to effect movement of the units in directions to stretch the work. 20
19. In a machine for stretching hides, skins, leather and other similar pieces of work and securing them in stretched condition, a support for a piece of work, a plurality of stretching and tacking units movable to engage edge portions of a piece of work on the support and subsequently movable away from each other upon opposite sides of the piece of work to effect stretching thereof, means individual to each unit for moving it in the directions described, means controlled by the work for rendering the moving means of each unit inoperative when its associated unit has engaged with an edge portion of the work, and means for rendering all of the moving means for all the units simultaneously operated whereby the units are caused to stretch portions of the work simultaneously in opposite directions from a central portion thereof. 25
20. In a machine for stretching hides, skins, leather and other similar pieces of work and securing them in stretched condition, a support for a piece of work, a plurality of stretching and tacking units movable to engage edge portions of a piece of work on the support and subsequently movable away from each other upon opposite sides of the piece of work to effect stretching thereof, a shaft individual to each stretching and tacking unit for causing the described movements thereof, a gear for driving all of the shafts, means controlled by the work for causing disconnection of each shaft from the driving gear when its associated unit has engaged with the work, and means for causing re-engagement of all of the shafts with the gear wheel to effect simultaneous movement of the units in directions to stretch the work. 30
21. In a machine for stretching hides, skins, leather and other similar pieces of work, a support for a piece of work, a plurality of stretching devices movable for engaging edge portions of a piece of work on the support and subsequently movable away from each other on opposite sides of the work to effect a stretching of the piece of work, individual means for causing the described movements of each device, feeler mechanism associated with each device for engaging with the piece of work to control the extent of movement of each device, and means automatically operative for controlling the moving means for the devices for causing movement of the devices simultaneously to effect a stretching of the piece of work. 35
22. In a machine for stretching hides, skins, leather and other similar pieces of work, a support for a piece of work, a plurality of de- 40

5 vices each comprising a gripper and movable in converging directions to engage edge portions of a piece of work on the support and also in diverging directions to stretch the piece of work, and individual means for causing the described movements of each device, said gripper having connections for controlling the moving means of its associated device, whereby the converging movement of each device is terminated when an edge portion of the work has been gripped.

10 23. In a machine for stretching hides, skins, leather and other similar pieces of work and securing them in stretched conditions, a support for a piece of work, a plurality of stretching devices for engaging edge portions of a piece of work subsequently operative for effecting a stretching operation upon the work, and a securing means associated 15 with each device and arranged to become operative when the tension on the edge portion reaches a predetermined maximum.

20 24. In a machine for stretching hides, skins, leather and other similar pieces of work and securing them in stretched condition, a work support having a surface upon which a piece of work may be spread out, and a plurality of stretching devices movable over the work supporting surface along converging 25 paths to engage a piece of work, each device having a gripper for seizing an edge portion of the piece of work during the converging movement of the devices so that the work may be stretched during movement of the devices 30 away from each other on diverging paths, each device also having means operative for securing in stretched condition a portion of the work operated upon by the associated gripper.

35 25. In a machine for stretching hides, skins, leather and other similar pieces of work and securing them in stretched condition, a table for supporting a board and a piece of work spread out thereon, a plurality of devices movable over the board for picking up and gripping edge portions of a piece of work and stretching it and each having means for securing a portion of the work to the board in stretched condition, and means for moving 40 the devices away from each other on opposite sides of the work to stretch the piece of work and to effect operation of the securing means.

45 26. In a machine for stretching hides, skins, leather and other similar pieces of work and securing them in stretched condition, a support for a piece of work, a plurality of devices for engaging and stretching a piece of work simultaneously in all directions from a central portion thereof, and a work securing means associated with each device and arranged to be controlled thereby for securing the work in stretched condition when a predetermined tension on the work is reached.

50 27. In a machine for stretching hides, skins, leather and other similar pieces of work

and securing them in stretched condition, a support for a piece of work, a plurality of stretching devices each guided for movement to engage an edge portion of a piece of work and for movement in a reverse direction to stretch the work, means for moving the devices in the directions stated, and securing means associated with each device and arranged to be controlled by the tension on the work, whereby the work is secured in stretched condition when a predetermined tension is reached between each individual device and the portion of work gripped thereby.

55 28. In a machine for stretching hides, skins, leather and other similar pieces of work and securing them in stretched condition, a support for a piece of work, a plurality of devices each having gripper means for engaging edge portions of the piece of work on the support, means individual to each device for moving the same in a direction to engage the work and also in a reverse direction to stretch the work, said gripper means serving as a feeler mechanism for engaging the work to control the moving means to terminate the movement of the device after the gripper has seized the work, means associated with each device for securing the work in stretched condition, and connections between the gripper means and the securing means to determine the time of operation of the latter means.

60 29. In a machine for stretching hides, skins, leather and other similar pieces of work and securing them in stretched condition, a support for a piece of work, a plurality of devices each having a gripper for engaging an edge portion of a piece of work on the support, means for moving the devices to cause the grippers to engage the work and for moving them subsequently in reverse directions to effect a stretching of the piece of work, and a securing means associated with each device to effect securing of the work when a predetermined tension has been established between the gripper and the gripped portion of the work, said securing means being operative to cause its associated gripper to release the work following the securing operation on the gripped edge of the work.

65 30. In a machine for stretching hides, skins, leather and other similar pieces of work and securing them in stretched condition, a support for a piece of work, a plurality of devices having each a gripper for engaging an edge portion of a piece of work during movement of the devices toward edge portions of the work, means for moving the devices simultaneously away from each other on opposite sides of the work to effect a stretching operation on the work, securing means associated with each device and arranged to be controlled by the gripper to effect securing of the portion of work held by

the gripper when a predetermined tension thereof has been reached, and connections between the securing means and its associated gripper to effect release of the work from the gripper immediately after the operation of the securing means.

31. In a machine for stretching hides, skins, leather and other similar pieces of work and securing them in stretched condition, a support for a piece of work, a plurality of devices for engaging and stretching a piece of work on the support, a securing means associated with each stretching device, means controlled by the stretching device for causing operation of the securing means on the work when a predetermined tension of the work has been reached, and connections between the securing means and its associated stretching device for causing the latter to release the work immediately after the operation of the securing means.

32. In a machine for stretching hides, skins, leather and other similar pieces of work and securing them in stretched condition, a support for a board and a piece of work spread out thereon, a plurality of devices movable over the board and each having a gripper for engaging an edge portion of a piece of work, said devices being movable away from each other on opposite sides of a piece of work to effect stretching operations thereon, a tacker mechanism associated with each device for securing a stretched portion of the work to the board, and connections between the gripper and the tacker mechanism for controlling the latter to set a tack before the work is released by the gripper.

33. In a machine for stretching hides, skins, leather and other similar pieces of work and tacking them in stretched condition, a work support, and a plurality of devices movable toward and away from a common center, each device having a gripper for seizing an edge portion of the piece of work during movement of the device toward the center so that the work may be stretched during movement of the devices away from the said center, each device also having means for driving a tack during movement of the device away from said center.

34. In a machine for stretching hides, skins, leather and other similar pieces of work and tacking them in stretched condition, a table for supporting a board and a piece of work spread out thereon, a plurality of devices movable over the board for gripping and for stretching a piece of work and having tacking means for tacking it to the board in stretched condition, and means for simultaneously moving the devices away from each other on opposite sides of the work to stretch the piece of work and to effect operation of the tacking means.

35. In a machine for stretching hides, skins, leather and other similar pieces of work

and tacking them in stretched condition, a support for a piece of work, and a plurality of devices for engaging and stretching a piece of work simultaneously in all directions from a central portion thereof, and a tacking means associated with each device and arranged to be controlled thereby for inserting a tack when a predetermined tension on the work is reached.

36. In a machine for stretching hides, skins, leather and other similar pieces of work, a support for a piece of work, a plurality of devices movable toward each other upon opposite sides of a piece of work in order to engage edge portions of the piece of work on the support, individual means for causing the described movement of each device, a gripper associated with each device for engaging an edge portion of the piece of work, said gripper having connections for controlling the moving means of its associated device, and means for reversing the direction of movement of the devices to put the piece of work under tension.

37. In a machine for stretching hides, skins, leather and other similar pieces of work, a support for a piece of work, a plurality of devices each having gripper means for engaging edge portions of the piece of work on the support, means individual to each device for moving the same in a direction to engage the work, said gripper means serving as a feeler mechanism for engaging the work and for controlling the moving means to terminate the movement of the device after the gripper has seized the work, and means for reversing the direction of movement of the devices and causing simultaneous movement of the devices to put the piece of work under tension.

38. In a machine for stretching hides, skins, leather and other similar pieces of work, a support for a piece of work, a plurality of devices for engaging edge portions of the piece of work on the support, means for moving the devices simultaneously toward the work, a feeler mechanism associated with each device for engaging with the work and operative to control the moving means for the devices so as to terminate the movement of the device after the latter has engaged with an edge portion of the work, and means for reversing the moving means to cause simultaneous movement of the devices along diverging paths to effect stretching of the piece of work.

39. In a machine for stretching hides, skins, leather and other similar pieces of work, a support for a piece of work, a plurality of devices movable along converging paths for engaging edge portions of the piece of work on the support and subsequently movable along diverging paths to effect a stretching of the piece of work, individual means for causing the described movements of each

- device, and feeler mechanism associated with each device for engaging with the nearest portion of the piece of work and operative to control the extent of converging movement of each device, and means automatically operative for controlling the moving means for the devices for causing movement of the devices simultaneously along diverging paths to effect a stretching of the piece of work.
40. In a machine for stretching hides, skins, leather and other similar pieces of work and tacking them in stretched condition, a support for a piece of work, a plurality of devices for engaging edge portions of a piece of work subsequently operative for effecting a stretching operation upon the work, and a tacking means associated with each device and arranged to be controlled thereby to become operative when the tension on the edge portion reaches a predetermined maximum.
41. In a machine for stretching hides, skins, leather and other similar pieces of work and tacking them in stretched condition, a support for a piece of work, a plurality of devices arranged to engage edge portions of a piece of work, means for moving the devices for effecting a stretching operation on the piece of work, and tacking means associated with each device and arranged to be controlled by the tension on the work, whereby a tack is driven into the work when a predetermined tension is reached between each individual device and the portion of work gripped thereby.
42. In a machine for stretching hides, skins, leather and other similar pieces of work and tacking them in stretched condition, a support for a piece of work, a plurality of devices arranged in a circle about a given center and guided for movement in converging paths to engage edge portions of a piece of work, means for moving the devices in diverging directions for effecting a stretching operation on the piece of work, and tacking means associated with each device and arranged to be controlled by the tension on the work, whereby a tack is driven into the work when a predetermined tension is reached between each individual device and the portion of work gripped thereby.
43. In a machine for stretching hides, skins, leather and other similar pieces of work, a support for a piece of work, a plurality of devices movable along converging paths, each device having a gripper for engaging an edge portion of the piece of work, means individual to each device for effecting movement thereof in a direction toward the work controlled by the gripper to terminate the movement of the device when the work has been securely gripped, and means for simultaneously moving all of the devices along divergent paths to effect a stretching operation of the piece of work.
44. In a machine for stretching hides, skins, leather and other similar pieces of work and tacking them in stretched condition, a support for a piece of work, a plurality of devices each having a gripper for engaging an edge portion of a piece of work on the support, means for moving the devices to engage the work and subsequently to effect a stretching of the piece of work, a tacker mechanism associated with each device having a tack driver and a locking means for holding the tack driver in raised position, and connections to the gripper for tripping the locking means when a predetermined tension has been established between the gripper and the gripped portion of the work to cause the driving of a tack.
45. In a machine for stretching hides, skins, leather and other similar pieces of work and tacking them in stretched condition, a support for a piece of work, a plurality of devices having each a gripper for engaging an edge portion of the work during movement of the devices toward edge portions of the work, means for moving the devices simultaneously along divergent paths to effect a stretching operation on the work, tacker mechanism associated with each device and arranged to be controlled by the gripper to effect a tacking of the work when a predetermined tension thereof has been reached, and means for automatically resetting each tacker mechanism to effect a driving of a tack in the next cycle of operations.
46. In a machine for stretching hides, skins, leather and other similar pieces of work and tacking them in stretched condition, a support for a piece of work, a plurality of devices for engaging and stretching a piece of work on the support, a tacker associated with each stretching device, means controlled by the stretching device for causing operation of the tacker to insert a tack when a predetermined tension of the work has been reached, and connections between the tacker and the gripper for causing the latter to release the work at the instant that a tack is driven into the stretched portion of work.
47. In a machine for stretching hides, skins, leather and other similar pieces of work and tacking them in stretched condition, a support for a piece of work, a plurality of devices each having a gripper for engaging an edge portion of the piece of work, means for moving said devices to effect stretching of the piece of work, a tacker mechanism associated with each device, and connections between the gripper and its associated tacker mechanism for controlling the latter to cause the driving of a tack in the stretched portion of the work and to cause the gripper to release the work at the instant of driving the tack into the work.
48. In a machine for stretching hides, skins, leather and other similar pieces of work and

- tacking them in stretched condition, a support for a piece of work, a plurality of stretching and tacking units each comprising a gripper for engaging an edge portion of the piece of work and a tacker for inserting a tack in the stretched portion of the work, said gripper having a movable jaw for engagement with the work, said tacker having a tack driver and a driver lever arranged to be locked with the driver in raised position, and connections between the tacker and the gripper arranged to trip the driver lever to effect operation of the tack driver when the gripper has caused a predetermined tension in the work, said connections being further operative to cause the gripper jaw to release the work as a tack is driven into the stretched portion thereof. 49. In a machine for stretching hides, skins, leather and other similar pieces of work and tacking them in stretched condition, a support for a piece of work, a plurality of stretching and tacking units each comprising a gripper for engaging an edge portion of the piece of work and a tacker for inserting a tack in the stretched portion of the work, said gripper having a movable jaw for engagement with the work, said tacker having a tack driver and a driver lever arranged to be locked with the driver in raised position, connections between the tacker and the gripper arranged to trip the driver lever to effect operation of the tack driver when the gripper has caused a predetermined tension in the work, said connections being further operative to cause the gripper to release the work after a tack has been driven into the stretched portion thereof, means for moving the stretching and tacking unit in a direction to cause the gripper to engage an edge portion of the work and subsequently in the reverse direction to effect a stretching operation of the work, and means controlled by the movement of the stretching and tacking unit to effect a resetting of the tack driver lever following the driving of a tack. 50. In a machine for stretching hides, skins, leather and other similar pieces of work and tacking them in stretched condition, a support for a piece of work, and means for stretching and tacking the piece of work comprising a unit having a gripper, a tacker, and connections between the gripper and the tacker for causing operation of the tacker when the gripper yields upon attaining a certain predetermined maximum of tension in the piece of work, said connections being operative also for controlling the gripper from the tacker whereby in the operation of the latter the gripper is caused to release the work as a tack is driven into the work. 51. In a machine for stretching hides, skins, leather and other similar pieces of work and tacking them in stretched condition, a support for a piece of work, a plurality of stretching and tacking units movable to engage marginal portions of the piece of work on the support and in directions away from each other upon opposite sides of the work to stretch engaged portions of the work, each unit comprising a gripper and a tacker, and tack supplying means mounted independently of the unit but arranged to be controlled thereby for supplying a tack to the tacker. 52. In a machine for stretching hides, skins, leather and other similar pieces of work and tacking them in stretched condition, a support for a piece of work, a plurality of stretching and tacking units movable to engage marginal portions of the piece of work on the support and in directions away from each other upon opposite sides of the work to stretch engaged portions of the work, each unit comprising a gripper and a tacker, said tacker comprising a tack pocket, and means for delivering a tack to the tack pocket comprising a delivery chute controlled by the movement of the unit to cause the delivery chute to discharge a tack into the tack pocket. 53. In a machine for stretching hides, skins, leather and other similar pieces of work and tacking them in stretched condition, a support for a piece of work, a plurality of stretching and tacking units movable to engage marginal portions of the piece of work on the support and in directions away from each other upon opposite sides of the work to stretch engaged portions of the work, each unit comprising a gripper and a tacker, said tacker having a tack pocket, and means for delivering a tack to the pocket comprising a delivery chute supported for rotary movement about its longitudinal axis and adapted to be operated through contact with the stretching and tacking unit to deliver a tack to the tack pocket. 54. In a machine for stretching hides, skins, leather and other similar pieces of work and tacking them in stretched condition, a support for a piece of work, a plurality of stretching and tacking units each movable toward a piece of work to engage a marginal portion thereof and in a reverse direction to effect a stretching operation on the work, a shaft for each unit for causing the described movements thereof, driving means common to all of the shafts, and a single member under the control of the operator for initiating operation of the driving means and simultaneously therewith moving the work support to work presenting position. 55. In a machine for stretching hides, skins, leather and other similar pieces of work and tacking them in stretched condition, a support for a piece of work, a plurality of stretching and tacking units each movable from an outer position of rest to engage an edge portion of a piece of work and in a reverse direction to effect a stretching opera-

tion on the work, a shaft for each unit operative to effect the described movement of the unit, driving means common to all of the shafts, each unit comprising a tacker mechanism constructed and arranged to receive and 5 to insert a tack in a stretched portion of the work, means for delivering tacks to all of the tacker mechanisms, said driving means being movable in reverse directions to cause 10 movement of the units toward the work and subsequently away from each other to stretch the work, and connections between said driving means and the tack delivering means for operating the latter to effect distribution of 15 tacks to the tacker mechanisms when the latter are in their outer positions of rest.

56. In a machine for stretching hides, skins, leather and other similar pieces of work and tacking them in stretched condition, a support for a piece of work, a plurality of stretching and tacking units each movable from an outer position of rest to engage an edge portion of the piece of work and in a reverse direction to effect a stretching 20 operation on the work, a shaft for each unit operative to effect the described movement of the unit, driving means common to all of the shafts, each unit comprising a tacker for inserting a tack in a stretched portion 25 of the work, tack supplying means associated with each unit, means for delivering tacks to all of said tack supplying means, said driving means being movable in reverse directions to cause movement of the units 30 toward the work and subsequently away from each other to stretch the work, and connections between said driving means and the tack delivering means for operating the latter to effect distribution of tacks to the tack supplying 35 means when the units are in their outer positions of rest.

57. In a machine for stretching hides, skins, leather and other similar pieces of work and tacking them in stretched condition, a support for a piece of work, a plurality of stretching and tacking units movable to engage an edge portion of a piece of work and in a reverse direction to effect a stretching 40 operation on the engaged portion of the work, means for moving the units in the direction described, each unit comprising a tacker mechanism for driving a tack in a stretched portion of the work, said tacker mechanism having a tack pocket for receiving a tack, and means for delivering a tack to the tack pocket arranged to be operated by contact with the stretching and tacking unit therewith to deliver a tack when the unit is in its outer position of rest.

58. In a machine for stretching hides, skins, leather and other similar pieces of work and tacking them in stretched condition, a support for a piece of work, a plurality of stretching and tacking units movable 45 to engage an edge portion of a piece of work

and in a reverse direction to effect a stretching operation on the engaged portion of the work, means for moving the units in the directions described, each unit comprising a tacker mechanism for driving a tack in a stretched portion of the work, said tacker mechanism having a tack pocket for receiving a tack, tack supplying means including a movable tack chute arranged to be controlled by the stretching and tacking unit to deliver a tack to the tack pocket, means for delivering a tack to each tack supplying means, and means controlled by the driving means for the stretching and tacking units for causing operation of the tack delivering 50 means.

59. In a machine for stretching hides, skins, leather and other similar pieces of work and tacking them in stretched condition, a support for a piece of work, means for stretching the work on the support, a plurality of tacking means for inserting a tack in the stretched portions of the work to hold the latter in stretched condition, a shaft for each tacking means, driving means common to all of said shafts comprising a pair of gears movable so that first one and then the other becomes the source of power whereby the stretching means and the tacking means are moved first in one direction and then in a reverse direction, tack supplying means associated with each tacking means, and means for delivering a tack to each tack supplying means arranged to be controlled by the movement of the pair of gears so that the delivering means becomes operative to deliver tacks when the plurality of tacking means are in their outer positions of rest.

60. In a machine for stretching hides, skins, leather and other similar pieces of work and tacking them in stretched condition, a support for a piece of work, a plurality of stretching and tacking units movable to engage edge portions of the piece of work and subsequently movable in a reverse direction to effect a stretching operation on the piece of work, means for causing the described movement of the stretching and tacking units comprising a pair of gears, a shaft upon which the gears are slidable so as to be engaged alternately with a source of power, means for supplying a tack to each tacking means comprising a plurality of chutes for delivering tacks to the tacking means, and means for delivering a tack to each chute arranged to be controlled by the shifting movement of the gears.

61. In a machine for stretching hides, skins, leather and other similar pieces of work and tacking them in stretched condition, a support for a piece of work, a plurality of stretching and tacking units movable to engage edge portions of a piece of work on the support and subsequently movable in a reverse direction to effect a stretching opera-

tion on the piece of work, means for causing the described movements of the stretching and tacking units comprising a pair of gears, a shaft upon which the gears are slideable so as to be engaged alternately with a source of power, means for supplying a tack to each tacking means comprising a plurality of chutes for delivering tacks to the tacking means, means for delivering a tack to each chute, and means controlled by one of the gears to cause the operation of said delivering means.

62. In a machine for stretching hides, skins, leather and other similar pieces of work and tacking them in stretched condition, a support for a piece of work, a plurality of stretching and tacking units movable towards each other from opposite sides of a piece of work to engage edge portions of the work, and movable in directions away from each other to stretch the work, each unit comprising a feeler for engaging with an edge portion of the work, a shaft individual to each unit for causing the described movements thereof, a member under the control of the operator for initiating operation of all of the shafts to cause movement of the units toward the work, means controlled by the feeler of each unit for disconnecting each shaft when its associated unit has engaged with an edge portion of the work, and means for rendering all of the shafts operable simultaneously to move all of the units in a direction to stretch the piece of work.

63. In a machine for stretching hides, skins, leather and other similar pieces of work and tacking them in stretched condition, a support for a piece of work, a plurality of stretching and tacking units movable toward each other from opposite sides of a piece of work to engage edge portions of the work, and movable in directions away from each other to stretch the work, each unit comprising a feeler for engaging with an edge portion of the work, a shaft individual to each unit for causing the described movements thereof, a member under the control of the operator for initiating operation of all of the shafts to cause movement of the units toward the work, means controlled by the feeler of each unit for disconnecting each shaft when its associated unit has engaged with an edge portion of the work, and means automatically operative for rendering all of the shafts operable simultaneously to move all of the units in a direction to stretch the piece of work.

64. In a machine for stretching hides, skins, leather and other similar pieces of work and tacking them in stretched condition, a support for a piece of work, a plurality of stretching and tacking units movable towards each other from opposite sides of a piece of work to engage edge portions of the work, and movable in directions away from each other to stretch the work, each unit com-

prising a feeler for engaging with an edge portion of the work, a shaft individual to each unit for causing the described movements thereof, a carrier for each shaft, a driving means common to all of the shafts, means under the control of the operator for causing engagement of all of the shafts with the driving means through depression of the carriers for the shafts, a latch for locking the carriers in their depressed positions with the shafts engaged with their driving means, means controlled by the feeler of each unit for causing unlocking of the latch of the associated carrier when the feeler engages with the work, and means for causing all of the shafts to become operative simultaneously to move all of the units in a direction to stretch the piece of work.

65. In a machine for stretching hides, skins, leather and other similar pieces of work and tacking them in stretched condition, a support for a piece of work, a plurality of stretching and tacking units movable towards each other from opposite sides of a piece of work to engage edge portions of the work, and movable in directions away from each other to stretch the work, each unit comprising a feeler for engaging with an edge portion of the work, a shaft individual to each unit for causing the described movements thereof, a driving means common to all of the shafts, means under the control of the operator for causing engagement of all of the shafts with the common driving means, means controlled by the feeler for releasing each shaft when its associated unit engages with an edge portion of the work, means for simultaneously re-engaging all the shafts with the driving means for causing movement of the units in a direction to stretch the work, and means automatically operative for disconnecting the shafts when the units have reached their outer positions of rest.

66. In a machine for stretching hides, skins, leather and other similar pieces of work and tacking them in stretched condition, a support for a piece of work, a plurality of stretching and tacking units movable towards each other from opposite sides of a piece of work to engage edge portions of the work, and movable in directions away from each other to stretch the work, each unit comprising a feeler for engaging with an edge portion of the work, a shaft individual to each unit for causing the described movements of each unit, a common driving means for all of the shafts, a carrier for each shaft, a member under the control of the operator for depressing the carriers simultaneously to cause engagement of the shafts with the common driving means, a latch for holding each carrier with its associated shaft in driving connection with the driving means, a trip controlled by each feeler for causing release of the carrier from the latch, thereby permit-

ting the associated shaft to become inoperative when the stretching and tacking unit engages with the edge of the work, means for simultaneously reconnecting the shafts with the driving means to cause movement of the units in a direction to stretch the work, and means for operating the trip of each unit to cause unlatching of the latch to permit the carrier to rise and thus disconnect the shaft 5 when the stretching and tacking unit reaches its outer position of rest.

67. In a machine for stretching hides, skins, leather and other similar pieces of work and tacking them in stretched condition, a support for a piece of work, a plurality of stretching and tacking units movable to engage an edge portion of a piece of work and movable in a reverse direction to perform a stretching operation on the work, a shaft 10 individual to each unit for causing the described movements of each unit, a driving member for all of the shafts, a latch member for locking the shafts in driving engagement with the common driving member, a trip for 15 each latch member arranged to be controlled by its associated unit for causing unlatching of the latch member when the unit engages with an edge portion of the work, and means for automatically re-engaging all of the 20 shafts with the common driving member, said trip being controlled by each unit to cause unlatching of the latch member to free the shafts from engagement with the common 25 driving member when each unit reaches its 30 outer position of rest.

68. In a machine for stretching hides, skins, leather and other similar pieces of work and tacking them in stretched condition, a support for a piece of work, a plurality of stretching and tacking units movable in one direction to engage marginal portions of a piece of work on the support and in the reverse direction to effect a stretching operation on the work, a shaft individual to each 40 unit for causing the described movements thereof, a member co-operating with the shaft for guiding each unit in its movements said unit being vertically movable with respect to both its shaft and its guiding member, where- 45 by different thicknesses of work may be presented to the units by the work support in the same position of the latter, means for driving the shafts to effect movement of the units toward the work, means controlled by 50 the units for causing disconnection of each shaft when the unit engages with an edge portion of the work, and means for causing re-engagement of the shafts with their driving means to cause movement of the units 55 away from each other to effect a stretching 60 operation on the work.

69. In a machine for stretching hides, skins, leather and other similar pieces of work, a gripper member for engaging an edge portion of the work comprising a roller, and

a gripper jaw having a portion provided with a plurality of corrugations for co-operation with the roller in gripping the work.

70. In a machine for stretching hides, skins, leather and other similar pieces of work, a gripper member for engaging an edge portion of the work, a pair of relatively thin-edged rollers mounted in spaced relation in the gripper member, and a gripper jaw for pressing the work against the rollers securely to grip the work. 75

71. In a machine for stretching hides, skins, leather and other similar pieces of work, a gripper for engaging an edge portion of the work comprising a pair of rollers, and a gripper jaw for pressing the work against the rollers securely to grip the work, said gripper jaw having a corrugation extending under both rollers and adapted to increase the grip of the jaw and rollers upon the work. 80

72. In a machine for stretching hides, skins, leather and other similar pieces of work, a gripper for engaging an edge portion of the work comprising a pair of rollers, and a gripper jaw for pressing the work against the rollers securely to grip the work, said gripper jaw having a corrugation extending under both rollers and adapted to increase the grip of the jaw and rollers upon the work, said corrugation being located when the jaw 90 is in gripping position beyond or in front of a plane passing vertically through the center of the rollers whereby any tendency of the rollers to slacken their grip through rotative movement is offset by an increased gripping 95 action. 100

73. In a machine for stretching hides, skins, leather and other similar pieces of work, a gripper for engaging an edge portion of the work comprising a roller, and a gripper jaw for pressing the work against the roller securely to grip the work, said gripper jaw having a corrugation extending under the roller and adapted to increase the grip of the jaw and roller upon the work. 105

74. In a machine for stretching hides, skins, leather and other similar pieces of work, a gripper for engaging an edge portion of the work comprising a roller, and a gripper jaw for pressing the work against the roller securely to grip the work, said gripper jaw having a corrugation extending under the roller and adapted to increase the grip of the jaw and roller upon the work, said corrugation being located when the jaw is in gripping position beyond or in front of a plane passing vertically through the center of the roller whereby any tendency of the roller to slacken its grip through rotative movement is offset by an increased gripping action. 110 115 120

75. In a tacking machine, a stationary chute section for receiving a tack from a source of supply, a movable chute section located below the stationary section and having a plate for closing the lower end of the stationary chute 125 130

section, a movable tack driving mechanism having a tack pocket for receiving a tack, and connections between the movable tack driving mechanism and the movable chute section for controlling the latter to cause the delivery of a tack to the tack pocket.

76. In a tacking machine, a stationary chute section for receiving a tack from a source of supply, a movable chute section located below the stationary section and having a plate for closing the lower end of the stationary chute section, means for mounting the movable chute section for oscillation, thereby causing said plate alternately to cover and to uncover the lower end of the stationary chute section, and a movable tack driving mechanism having connections to cause oscillation of the movable chute section whereby the latter is caused to deliver a tack to the tack driving mechanism.

77. In a tacking machine a stationary chute section for receiving a tack from a source of supply, a movable chute section located below the stationary section and having a plate for closing the lower end of the stationary chute section, said movable chute section having a lower end portion bent away from the axial line of the body of the chute section, means for mounting the movable chute section for oscillation about said axial line, and a tack driving mechanism having a pocket to position a tack for driving and movable to cause oscillation of the movable chute section whereby its lower end is brought into operative relation with respect to the tack pocket to deliver a tack thereto.

78. In a machine for stretching hides, skins, leather and other similar pieces of work and securing them in stretched condition, a support for a piece of work, a plurality of devices each having a gripper for engaging an edge portion of a piece of work, means individual to each device for effecting movement thereof in a direction toward the work and controlled by the gripper to terminate the movement of the device when the work has been securely gripped, means for simultaneously reversing the movement of all of the devices to effect a stretching operation on the piece of work, and means for securing the stretched piece of work in stretched condition.

In testimony whereof I have signed my name to this specification.

WILLIAM A. ELLISON.
